MAGAZINE STAND

Donald A. Walker, Kingston, Pa.

Application June 24, 1949, Serial No. 3,496

Term of patent 3½ years

(Cl. D33—2)

To all whom it may concern:

Be it known that I, Donald A. Walker, a citizen of the United States, residing at Kingston, in the county of Luzerne and State of Pennsylvania, have invented a new, original, and ornamental Design for a Magazine Stand, of which the following is a specification, reference being had to the accompanying drawing, forming part thereof.

Figure 1 is a view in top plan of a magazine stand embodying my design;

Figure 2 is a view in side elevation, the opposite side being similar; and

Figure 3 is a view in side elevation in a quarter relation to Figure 2, the opposite side being similar.

I claim:

The ornamental design for a magazine stand, substantially as shown and described.

DONALD A. WALKER.
